UNITED STATES PATENT OFFICE.

CHARLES F. PUTNAM, OF FITCHBURG, MASSACHUSETTS.

DESIGN FOR A VEHICLE-BODY.

SPECIFICATION forming part of Design No. 35,739, dated February 11, 1902.

Application filed December 16, 1901. Serial No. 86,167. Term of patent 14 years.

To all whom it may concern:

Be it known that I, CHARLES F. PUTNAM, a citizen of the United States, residing at Fitchburg, in the county of Worcester and State 5 of Massachusetts, have invented and produced a new and useful Design for a Vehicle-Body, of which the following is a specification.

The figure represents a side elevation of my new design.

As shown in the drawing, the leading or material feature of my design consists in providing the body of the vehicle with a front portion that is extended downward below the plane of the base-line of the remaining portion.

In the drawing the front part of the body is indicated by the letter A and the body proper by the letter B. Between the front portion A and the body portion B the side 20 rails are cut out in curved lines to form the entrance to the rear seat C. The base-line D is substantially straight from the rear or tail end of the body to a point near the front, at which latter point the body is extended down-

ward, as at E, so that the front end of the 25 body has its base-line dropped below the base-line of the remaining portion of the body, said latter base - line and the base - line of the dropped front portion joining each other by the inclined wall F. The dropped front portion of the body has also an inclined front wall G, and the upper part of said dropped portion constitutes a seat-frame which lies in a plane horizontally below the plane of the main seat-frame behind it. 30

Having described my invention, what I claim as new, and desire to secure by Letters Patent, is—

The design for a vehicle-body, as herein shown and described. 35

In testimony whereof I have hereunto set my hand in presence of two subscribing witnesses.

CHARLES F. PUTNAM. 40
